UNITED STATES PATENT OFFICE

EDGAR R. HARVEY, OF MEMPHIS, TENNESSEE

FEED WATER HEATER FOR BOILERS

Application filed August 30, 1930. Serial No. 478,975.

This invention relates to feed-water heaters for locomotives, and particularly to one which is interposed in the path of the exhausting gases of a locomotive fire-box so as to utilize this heat, which would otherwise be wasted.

The object of the invention is to provide a heater, of the character described, which may be inserted laterally through the side of a locomotive, and which is provided with means for allowing the water therein to circulate with the water in the boiler of the locomotive to which it is applied. Another object is to provide a heater which will accomplish the just mentioned object, and which is of extremely simple construction. Other objects may later become apparent.

In the accompanying drawings:

Figure 1 is a side view of a locomotive, a practical embodiment of the present invention being applied thereto.

Figure 2 is an enlarged partially cross sectioned side view of the invention removed from the locomotive.

Figure 3 is a longitudinal cross section thereof.

Figure 4 is a longitudinal cross section of the front end portion of the locomotive, showing the heater positioned therein.

Figure 5 is a lateral cross section of the front end of the locomotive, showing the heater as it appears from this end.

In the drawings, in which similar numerals refer to similar parts throughout the several views, there is shown a locomotive 10 having a feed water injector 11 of the conventional type. This injector is connected through a pipe 12 to the boiler of the locomotive, a water tank 13 being arranged so that the water must first pass therethrough. The tank 13 is of an elongate shape and having on one end a flange 14 which is shaped to fit the curvature of the locomotive's exterior sides. This tank is inserted laterally through the locomotive, whose sides are apertured for this purpose, so as to be slantingly positioned near the exhaust end of the boiler 15 of the locomotive, so that the exhaust gases and smoke must pass under it before they are discharged through the smoke stack

16 of the locomotive. The locomotive is shown equipped with the conventional spark arresting screen 17, and steam exhaust pipe 18 which creates a draft in the smoke box. The opposite side of the tank 13 is formed with a shoulder 19, which abuts the interior wall of the locomotive shell, while on the exterior wall a gasket 20 is pressed by a retaining end plate 21 both gasket and end plate being provided to be inserted over the shoulder end of the tank. The flange 14, the end plate 21, and the gasket 20 are preferably fixed to the locomotive by bolts and nuts 22, so that the tank may be easily removed if damaged. The tank is provided with removable clean out plugs 23 at each of its end corners, and with coupling openings 24 which are positioned on its sides proximate each corner. As shown two of these coupling openings are closed by plugs 25, a double number of openings being provided to enable the tank being used with any type of locomotive, no matter on which side its feed-water injector may be positioned.

The pipe 12, which connects the injector 11 to the tank 13, is coupled to a bottom opening in the tank and a short pipe 25 is coupled to a top opening therein, this pipe feeding directly to the water boiler of the locomotive. The pipe 12 is provided with a branch pipe 26, check valves 27 and 28 being interposed respectively in each of these last-named pipes.

When the water is injected to the boiler, through the injector 11, the valve 27 will open to permit the water carried in the tank 13 to be forced into the boiler of the locomotive, the valve 28 being forced closed preventing discharge of cold water into the bottom of the boiler by short cutting through the branch pipe 26. When the injector 11 is not being operated, the tank 13 will be in open circulation with the boiler, as the valve 28 will open to admit of thermosiphonic circulation. A hand valve 29 may be supplied to the pipe 12 so that the water feeding therethrough may be positively cut off.

This invention provides a feed-water heater of simplified design, which may be readily removed from a locomotive for repairs, and

which, when not actually injecting water into the boiler of a locomotive, is in open circulation therewith to prevent the formation of steam within the system.

5 It is to be understood that this invention is not to be limited to the particular form here shown and described, but that the appended claims are to be broadly construed.

I claim:

10 1. A feed-water heater for locomotives provided with boilers and water injectors, comprising an elongate tank having apertures formed at its top and bottom portions and with a flange at one end and a reduced opposite end forming a shoulder, said tank being adapted to be arranged laterally through the shell of the boiler so that said flange abuts the exterior thereof, a collar for insertion over the reduced end of said tank and against the exterior of the shell of the locomotive, when said shoulder rests against the interior of the shell, a pipe provided to connect a top aperture of said tank to the boiler at a point beneath the water line thereof, a pipe provided to connect the water injector to a bottom aperture of said tank, said last named pipe being provided with a branch pipe which is adapted to connect with the bottom of the boiler, and check valves interposed in said last named pipe and its branch pipe.

25 2. In a feed-water heater for a boiler, an elongated tank provided with a flange integral therewith and adjacent one extremity thereof, the flange being formed to receive means for securing the flange to support the heater in an operative position, said tank being so reduced near its other extremity as to form a shoulder on the elongated surface of said tank near the last mentioned extremity.

30 3. In a feed-water heater for a boiler, an elongated tank provided with a flange integral therewith and adjacent one extremity thereof, the flange being formed to receive means for securing the flange to support the heater in an operative position, said tank being so shaped near its other extremity as to form a shoulder on the elongate surface of said tank near the last mentioned extremity.

EDGAR R. HARVEY.
